DESIGN FOR A PARKING METER CASING

Ralph R. Smith, Fairview Village,
Cleveland, Ohio

Application June 5, 1937, Serial No. 69,688

Term of patent 7 years

To all whom it may concern:

Be it known that I, Ralph R. Smith, a citizen of the United States, residing at Fairview Village, Cleveland, in the county of Cuyahoga and State of Ohio, have invented a new, original, and ornamental Design for a Parking Meter Casing, of which the following is a specification, reference being had to the accompanying drawing, forming a part thereof.

In the drawing, Figs. 1, 2, 3, and 4 are respectively top, front, side, and rear views of a parking meter casing illustrating my new design.

I claim:

The ornamental design for a parking meter casing, substantially as shown.

RALPH R. SMITH.
